UNITED STATES PATENT OFFICE

AUSTIN E. COFRIN, OF GREEN BAY, WISCONSIN

METHOD OF SMOOTHING STOCK ON FOURDRINIER WIRE

Application filed March 25, 1931. Serial No. 525,271.

The invention relates to paper making machines of the Fourdrinier type and has as an object the provision of means to form an even layer of stock upon the wire whereby to improve the sheet.

It is a further object of the invention to provide means to smooth out ripples in the stock closely adjacent the breast roll of the machine, or at any other location that might 10 be made desirable to smooth out the ripples in the stock.

It is a further object of the invention to provide a smoothing roll in contact with the surface of the layer of the stock upon the 15 wire placed closely adjacent the breast roll for the purpose of smoothing out ripples in the stock.

Further objects of the invention will appear from the following description when 20 read in connection with the accompanying drawing showing an illustrative embodiment of the invention and wherein:

Fig. 1 is a central vertical section, parts being shown in elevation; and

Fig. 2 is a detail side elevation of driving means for the roll showing portions of the machine in section.

As shown the device comprises a vat for stock as at 10, a breast roll 11 having a Fourdrinier wire 12 running thereabout and supported by conventional tube rolls at 13. A deckle pulley is shown at 14 and a deckle strap at 15.

The described portions of the Fourdrinier 35 machine are conventional.

To accomplish the objects of the invention there is shown a smooth surfaced roll 16, which may be hollow if desired for lightness, which as shown is mounted in bearings 17 at 40 the opposite sides of the wire, and which roll may be positively driven by beveled gears 18 and drive shaft 19.

The objects of the invention may be secured by driving the roll either in the direction of the wire at a speed greater than the wire or in a reverse direction, that is, counter to the wire, so as to produce a still greater variation between the relative speeds of the wire and the roll. When the roll is driven 45 counter to the wire, it is preferred to provide

a small doctor plate or scraper as indicated at 20 which will strip the water from the surface of the roll 16 and prevent it from adhering to the surface of the roll to be thrown by centrifugal force down upon the sheet upon 55 the side thereof toward the dry end of the machine, which action would damage the forming sheet.

By use of the invention it is found that the ripples which are always present adjacent the breast roll, until they have time to flow laterally and smooth out, are immediately smoothed out so that the sheet may begin to form uniformly across its width and a thin sheet of tissue paper may thus be produced 60 65 which is much more uniform in quality.

Minor changes may be made in the invention within the scope of the appended claims without departing from the spirit thereof.

I claim:

1. The process of smoothing the surface of stock upon a Fourdrinier wire which comprises placing a smooth surfaced roll to dip into the layer of stock and causing the roll to revolve in a direction and at a speed to provide relative motion between the surface of the roll and the layer of stock.

2. The process of smoothing the surface of stock upon a Fourdrinier wire which comprises placing a smooth surfaced roll to dip into the layer of stock and causing the roll to revolve in a direction counter to the direction of movement of the layer of stock.

In testimony whereof I affix my signature.

AUSTIN E. COFRIN.
